United States Patent Office

Des. 218,391
Patented Aug. 18, 1970

218,391

CRADLE

Arthur W. Hopkins, Stone Bridge Road,
Cornwall, N.Y. 12518

Filed Feb. 13, 1969, Ser. No. 15,766

Term of patent 14 years

Int. Cl. D6—01

U.S. Cl. D5—5

Fig. 5

Fig. 6

Fig. 7

Fig. 8

FIG. 1 is a perspective view of a cradle showing my new design;

FIG. 2 is an end elevational view thereof;

FIG. 3 is a bottom plan view thereof;

FIG. 4 is a side elevational view thereof;

FIG. 5 is a perspective view of another embodiment of a cradle showing my new design;

FIG. 6 is an end elevational view thereof;

FIG. 7 is a bottom plan view thereof; and

FIG. 8 is a side elevational view thereof.

I claim:

The ornamental design for a cradle, as shown and described.
